FAN

Robert D. Moore, Marceline, Mo., assignor to The Moore Company, Marceline, Mo., a corporation of Missouri
Filed Nov. 13, 1959, Ser. No. 852,695
8 Claims. (Cl. 170—160.52)

This invention relates to fans for use in moving streams of air and similar gaseous fluids in substantially large volumes, and particularly a fan of this character having a construction adapted to the use of light weight materials in the manufacture thereof.

Fans of this character include a hub to which the blades are resiliently and sometimes adjustably connected, such as disclosed in Patent No. 2,471,578, issued to me on May 31, 1949. It is now found desirable to provide a fan having substantially greater flexibility to give better protection to the blades in turbulent fluids, where the blade load fluctuates widely.

Therefore, the principal objects of the invention are to provide a fan of this character having a blade mounting to give greater flexibility and whereby the blades swing freely so that centrifugal force balances out the air loads of lift and drag when the fan is in operation, and to provide a structure to limit drop of the blades when the fan is idle.

Other objects of the invention are to provide a simple and reliable structure particularly adapted for production of light weight materials such as wrought aluminum with a pure aluminum coating to resist corrosion when operating under corrosion creating conditions; to provide a substantially strong and rigid blade and hub structure while providing a resilient connection therebetween; and to provide a highly flexible connection that safely and securely anchors the blades to the hub.

In accomplishing these and other objects of the invention as hereinafter pointed out, I have provided improved structure, the preferred form of which is illustrated in the accompanying drawing, wherein:

FIG. 1 is a side elevational view of a part of a fan constructed in accordance with the present invention and which, for simplicity and clarity, illustrates the hub with a single blade mounted thereon.

FIG. 2 is a cross section through the flexible mounting, with the section being taken on the line 2—2 of FIG. 1, particularly illustrating the flexible connection feature of the invention.

FIG. 3 is a section on the line 3—3 of FIG. 1.

FIG. 4 is a fragmentary perspective view showing the hub end of one of the blades and parts of the pivotal connection shown in disassembled, spaced relation.

FIG. 5 is a perspective view of one of the clevis members that are secured to the hub.

FIG. 6 is a cross section through the flexible connection, taken on the line 6—6 of FIG. 2.

FIG. 7 is a diagrammatic front view of the fan illustrating the drag load.

FIG. 8 is a diagrammatic side view illustrating lift load.

Referring more in detail to the drawing:

1 designates a fan constructed in accordance with the present invention and which includes a hub 2 carrying a plurality of generally radially directed blades 3 that are mounted on the hub 2 by flexible connections 4. The hub 2 includes a main part 5 having a disk portion 6, a laterally directed annular flange 7 projecting from one side thereof, and an axial collar 8 projecting from the opposite side. The collar 8 has an axial bore 9 by which the hub is mounted upon and suitably keyed to an operating shaft, not shown. The hub 2 also includes a ring part 10 conforming in inner and outer diameter to the inner and outer diameter of the flange 7 and which is fixed thereto by bolts 11. The flange 7 and facing side

2

of the ring part are provided with substantially semicircular notches 12 and 13, circumferentially spaced about the periphery thereof and internally threaded as at 14 to mount clevises 15. The number and spacing of the notches 12 and 13 depend upon the number of blades to be mounted upon the hub.

The clevises 15 are best illustrated in FIG. 5, and each includes a yoke 16 having a disk shaped base 17 and extending from the base at one side thereof are diametrically spaced apart ears 18 and 19. The ears 18 and 19 have openings 20 and 21 for passing a fastening or pivot member 22, later to be described.

Extending from the opposite side of the base 17 is an externally threaded stem 23 having a diameter to be turned into the internally threaded notches in the parts of the hub and to cooperate with the base in providing an annular shoulder 24. The notches 12 and 13 are so formed in the hub that when the stems 23 are turned therein, the ring part 10 of the hub is slightly spaced from the flange 7 to provide a gripping action on the stems of the clevises when the bolts 11 are tightened, to thereby retain the ears of the yoke at the proper angle relatively to the rotational direction of the fan to maintain the desired pitch for the fan blades 3.

25 The fan blades 3 may be of a suitable construction and contour to effect efficient movement of the air, as determined by engineering practice. The fan blades also have shanks 25. The shanks 25 are formed by a plurality of angle members 26, each preferably composed of wrought aluminum and having a pure aluminum coating. The angle members 26 are arranged in spaced apart assemblies 27 and 28, wherein legs 29 of two of the angle members in each assembly are in lapping relation and reinforced by a plate 30 to provide relatively rigid webs 31 30 of the angle assemblies 27 and 28. The other and shorter legs 33 of the angles project outwardly and laterally from the webs 31 for attaching plate assemblies 34 and 35 to provide a substantially rigid boxlike cross section, as best illustrated in FIGS. 2, 3 and 4. The legs 29, 35 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 freedom of movement in the rotary direction of the fan. The ends of the mounting sleeve or bushing 44 project from the ends of the thimble and are convexly curved as at 46 to correspond with the inner curvature 47 of the ears 18 and 19 of the clevises and prevent turning of the mounting sleeve therein when the blades are assembled in the hub of the fan.

The pivot member 22 extends through the bore 48 of the mounting sleeve 44 and through the registering openings 29 and 21 of the ears. The ends of the pivot member 22 project from the outer sides of the ears of the clevises and threads 49 and 50 are provided for applying jam nuts 52 and 53, washers 54 and 55 being preferably inserted between the jam nuts and the outer sides of the ears, as shown in FIG. 2. One jam nut may be fixed to its end of the pivot member 22 by welding or the like, so that it in effect constitutes a head in the manner of a bolt, while the jam nut at the opposite end is adapted to be tightened for drawing the parts together in their assembled relation, as best shown in FIG. 2.

When the parts are assembled, the diameter of the fan may be adjusted to an over or under sized throat by loosening the bolts 11 and turning the stems 23 into or out of the hub, as the case may require, after which the bolts are retightened to maintain the adjustment.

The clevises are also set so that the axis of each pivot member 22 is positioned substantially at right angles to the resultant forces of the lift and drag. The lift and drag might vary with turbulence of the fluid stream, but the resultant of the two forces remains substantially the same, so that after the angle of the pivot member is fixed, it remains the same. For example, in the position illustrated the angle of the pivot member and mounting sleeve is about 10° relatively to a plane that extends at right angles to the axis of rotation. The center of gravity of each blade 3, designated "C.G." in FIG. 7, is located in lag, that is, on the retractive side of a radial line "a" extended from the center of the fan hub, so that torque exerted by the driver of the fan is converted to tension acting along the axis "b" of the fan blade. Thus the pivotal connection of point "c" to the hub pulls the blade in an endwise direction and without producing bending forces under the drag load.

The lift load acting on the front of the blade as indicated in FIG. 8 is counteracted by centrifugal force which tends to hold the axis of the blade in the plane indicated by the center line "d" extending generally transversely of the axis of hub rotation. If desired, the angle of the blades might be adjusted by turning the clevises within the hub.

It is obvious that the blades of the fan have pivotal movement on the hub by reason of the resilient sleeve 45. Consequently, the blades are free to adjust themselves when the fan is in operation and thereby eliminate tendency of the blades to bend and break under drag and lift loads, particularly when operating under turbulent conditions.

With the above described blade mounting, the blades have relatively free swinging movement under centrifugal force to balance out loads of lift and drag when the fan is in operation. The drop of the blades from their operative positions is limited when the fan is stopped by the ends of the shanks engaging the bases of the clevises. If it is desired, the space between the hub and inner edges of the blades may be closed by attaching segments (not shown) to studs 56 that are carried by the plate assembly 35 (FIG. 1).

From the foregoing, it is obvious that I have provided a fan wherein the blades have substantially free swinging movement and a greater resilient action under operative conditions by reason of the relation of the resilient sleeve to the transverse pivotal member 22. It is also obvious that I have provided a simpler and less expensive construction, and which is especially adapted to the production of fans from light weight materials while utilizing

ing a strong and rigid assembly of the parts of the hub, clevises, and shanks of the blades.

What I claim and desire to secure by Letters Patent is:

1. In a fan of the character described, a hub, a blade having a shank, and means pivotally connecting the shank on the hub for pivotal movement of the blade on an axis transverse of the axis of rotation of the hub for centrifugal force to balance air loads of lift and drag when the fan is in operation, and said blade having a center of gravity in lag from a radial line extending through the axis of rotation and said pivotal connection being in advance of said line to hold the shank of the blade in tension during rotation of the fan.

2. In a fan, a fan blade having a shank including spaced apart angle member assemblies, each including two angles with legs thereof in interlapping contact and reinforced by a backing plate, the other of said legs of the angles extending outwardly, and plates connecting the latter legs of the assemblies to provide a shank of boxlike cross section.

3. In a fan, a fan blade having a shank including spaced apart angle member assemblies, each including two angles with legs thereof in interlapping contact and reinforced by a backing plate, the other of said legs of

25 the angles extending outwardly, plates connecting the latter legs of the assemblies and in cooperation with the overlapping legs to provide a shank of boxlike section, said interlapping of the angles and said backing plate having registering openings extending therethrough, a 30 thimble extending across said boxlike section and having ends thereof fixed within said openings and secured from rotation therein, a resilient sleeve within the thimble, and a mounting sleeve extending through the resilient sleeve.

4. In a fan of the character described, a hub having a 35 main part and a ring part each having registering radially disposed internally threaded notch portions, a clevis having a threaded stem engaging the threads of the notches, said clevis also having spaced apart ears, fastening devices extending through said parts of the hub to draw said

40 parts together in clamping contact with the stem of the clevis with said ears being generally transversely of the hub, a fan blade having a shank, a thimble carried by the shank, a resilient sleeve in the thimble, a mounting sleeve extending coaxially through the resilient sleeve, and a clamping member extending through the mounting sleeve and having ends abutting the ears of the clevis for preventing rotation of the mounting sleeve so that the thimble of the fan blade turns on the mounting sleeve in a direction generally transversely of the rotational axis 50 of the hub by position of the ears on said hub, and said shank having a part adapted to contact a part on said hub for limiting pivotal movement of the fan blade.

5. In a fan of the character described, a hub, a fan blade having a shank, a thimble carried by the shank and having an axis extending transversely of the rotational axis of the blade, a mounting sleeve, a resilient sleeve within the thimble for resiliently supporting the thimble on the mounting sleeve, and a clamping member extending through the mounting sleeve for securing the mounting sleeve from turning on the hub, whereby the thimble

60 moves on the mounting sleeve by the resiliency of the resilient sleeve, said shank having a part adapted to contact a part on the hub for limiting movement of the fan blade relatively to the radial line extending through said axis of rotation.

6. In a fan of the character described, a hub, a fan blade having a shank, a thimble carried by the shank and having an axis extending transversely of the rotational axis of the blade, a mounting sleeve, a resilient sleeve within the thimble for resiliently supporting the thimble on the mounting sleeve, and a clamping member extending through the mounting sleeve for securing the mounting sleeve from turning on the hub, whereby the thimble

70 moves on the mounting sleeve by the resiliency of the resilient sleeve to provide a pivotal connection for

the fan blade so that centrifugal force balances air loads of lift and drag when the fan is in operation, and said blade having a center of gravity in lag from a radial line extending through the axis of rotation of the hub and said pivotal connection being in advance of said line to hold the shank of the blade in tension during rotation of the fan.

7. In a fan, a fan blade having a shank including spaced apart angle member assemblies, each including two angles with legs thereof in interlapping contact and reinforced by a backing plate, the other legs of the angles extending outwardly to provide flanges, plates connecting said flanges of the angle member assemblies and cooperating with the interlapping legs to provide a shank of boxlike section, said interlapping legs of the angles and said backing plates having openings extending therethrough, a thimble extending across said boxlike section and having ends thereof fixed within said openings against rotation therein, a resilient sleeve within the thimble, a mounting sleeve extending through the resilient sleeve, a hub, a clevis fixed to the hub and having spaced apart ears engaging the ends of the mounting sleeve therebetween, and a fastening member extending through the mounting sleeve and through the ears for clamping the ears to the end of the mounting sleeve, said thimble being movable on the mounting sleeve by the resiliency of said resilient sleeve.

8. In a fan, a fan blade having a shank including spaced apart angle member assemblies, each including two angles with legs thereof in interlapping contact and reinforced by a backing plate, the other legs of the angles

extending outwardly to provide flanges, plates connecting said flanges of the angle member assemblies and cooperating with the interlapping legs to provide a shank of boxlike section, said interlapping legs of the angles and said backing plates having openings extending therethrough, a thimble extending across said boxlike section and having ends thereof fixed within said openings against rotation therein, a resilient sleeve within the thimble, a mounting sleeve extending through the resilient sleeve, a hub, a clevis fixed to the hub and having spaced apart ears engaging the ends of the mounting sleeve therebetween, and a fastening member extending through the mounting sleeve and through the ears for clamping the ears to the end of the mounting sleeve, said thimble being movable on the mounting sleeve by the resiliency of said resilient sleeve to provide a pivotal connection so that centrifugal force balances air loads of lift and drag when the fan is in operation, and said blade having a center of gravity offset from a radial line extending through the axis of rotation and said pivotal connection being in advance of said line to hold the shank of the blade in tension during rotation of the fan.
